UNITED STATES PATENT OFFICE.

LEVI S. GARDNER, OF NEW ORLEANS, LOUISIANA, ASSIGNOR TO GARDNER CAR-BURETOR & BRASS WORKS, OF SHREVEPORT, LOUISIANA, A CORPORATION OF LOUISIANA.

CARBURETER.

1,095,101.

Specification of Letters Patent. Patented Apr. 28, 1914.

Application filed June 19, 1906, Serial No. 322,380. Renewed August 12, 1911. Serial No. 643,783.

To all whom it may concern:

Be it known that I, Levi S. GARDNER, a citizen of the United States, residing at New Orleans, parish of Orleans, State of Louisiana, have invented a certain new and useful Improvement in Carbureters, and declare the following to be a full, clear, and exact description of the same, such as will enable others skilled in the art to which it pertains to make and use the same, reference being had to the accompanying drawings, which form a part of this specification.

My invention has for its object the production of valve regulating mechanism for use more particularly in connection with carbureters for explosive engines, but as will be seen when I have described the invention in detail, it can be used in many other forms of devices and for many other purposes.

In the present construction of carbureters it is usual to provide the valve controlling the inlet of air with a spring adjustable as to its tension, independent thereof a throttle valve for admitting the mixture to the engine cylinder, and independent of both a needle valve controlling the admission of the gasolene. The difficulty with this form of carbureter is that when it is set with the proper tension on the spring controlling the air inlet for a partly closed throttle, that tension is not necessarily proper with a wide open throttle. This objection, together with others which are to be found in the present construction of carbureters, are overcome by my improved construction.

The objects of my invention are as follows: 1. To provide a carbureter in which the valve controlling the air inlet is positively moved. 2. To provide a carbureter in which the air inlet valve and the throttle are simultaneously moved to control the speed of the engine. 3. To provide a carbureter in which the vacuum space between the air inlet valve and the throttle can be easily varied by the adjustment of either the air inlet valve or the throttle valve or both. 4. To provide a carbureter in which the oil or gasolene feed and the feed of air are so connected that as the oil or gasolene feed is increased or decreased, the amount of air fed will be correspondingly increased or decreased in the proper proportion. 5. To provide a carbureter in which the air

inlet valve and the throttle valve can be simultaneously operated to open and close them, and in which when they are once adjusted so that the vacuum space between them when once set to accommodate an engine running at low speed for instance, will be properly increased in size or capacity so that as the speed of the engine is increased the proper mixture will still be fed to the cylinder. These various objects are attained by the embodiment of my invention shown in the drawings herewith, which I will now proceed to explain in detail.

Figure 1 is a plan view of my structure with parts broken away on the line 1—1 of Fig. 2. Fig. 2, is a vertical section on the line 2—2 of Fig. 1. Fig. 3, is a view of the under side of the structure. Fig. 4, is a side elevation looking in the direction of arrow 4 of Fig. 1.

In carrying out the invention, A represents what may be termed the main casing or body of the carbureter, provided with screw threads a whereby it may be attached to the intake pipe of the cylinder. It is provided on its lower end with screw threads a' , by which it is engaged to a lower casing B, the extending flange a^2 on the casing A and the extending flange b and vertical wall b' constituting the combustible fluid chamber B'. The casing A is bored longitudinally as at B ^{2} and projecting inwardly from the interior wall of the casing A is a flange a^3 . Projecting inwardly from the interior wall of the casing B is a flange b^2 which abuts the flange a^3 . Extending through the flange b^2 are the fluid feed ducts C leading from the chamber B' up to the face of the flange b^2 .

D is the oil or gasolene inlet pipe controlled by the valve D' carried by the valve stem D ^{2} , the latter being attached to a float D ^{3} so that when the fluid in the chamber B' reaches a proper height, the admission of the fluid into the chamber B' will be cut off and the amount thereof in the chamber is thus regulated. Extending from the interior wall of the casing A are arms E carrying a bearing E' in which a valve stem E ^{2} slides. On this valve stem is a valve F. The stem E ^{2} extends down to a point below the casing B where it is provided with a projection e, the purpose of which will be later explained. Surrounding the stem E ^{2} below

the valve F is a sleeve or stem G carrying a valve G'. A bearing H carried by the arms h which extend inwardly from the interior wall of the casing B slidably supports the stems G and E². The stem G is provided on its lower end with a projection g. Carried by the arm J is a plate J' of curved shape, as shown in Fig. 3, and having in its face grooves j, j', the pin e entering and travel-
 10 ing in the groove j while the pin g enters and travels in the groove j'. The arm J is pivotally engaged to one end of this plate J' and pivotally engaged to the other end of this plate J' is an arm K.
 15 Extending from the casing B is a fixed bearing M and a split bearing M', the latter being shown in Figs. 2 and 3. On the arm J is a stem J² bored longitudinally to receive the stem K' of the arm K,
 20 the stem J² fitting the bearing M and revolu-
 25 ble therein. The upper end of this stem J² is interiorly screw-threaded as at j², and screwed therein is a nut J³. Surrounding this nut J³ is the nut J⁴, the upper end of which bears against the shoulder j³ on the nut J³. This nut J⁴ is threaded exteriorly as at j⁴ to fit the interior threads of the split bearing M'. The upper end of the stem K' is screw-
 30 threaded as at h to fit into the nut K² and this latter nut fits in the upper end of the nut J³, the two being engaged or keyed together by the pin h' to prevent the nut K² from being withdrawn from the nut J³ and yet allowing it to revolve therein. The result of the
 35 structure just described is that by turning the nut K² the stem K' and consequently the arm K will be adjusted vertically with respect to the arm J. This vertical adjustment of the arm K will raise or lower the
 40 end of the plate J' with respect to the opposite end to which the arm J is pivoted. On the end of the arm J is an eye J⁵, by means of which the arm J can be connected up with any suitable mechanism extending to the operator. It will be observed that the vertical stem J² of the arm J revolves in a horizontal direction in the nut J⁴ and the bearing M and that when the arm J is thus
 45 swung horizontally it will carry with it the plate J' so as to cause the diagonal grooves j, j' to act upon the pins e, g, and thereby move the stems E² and the stem G vertically, thus carrying the valve F to and from its seat a⁸, and the valve G' to and from its seat b². On the bottom of the casing B is a projecting lug N and located therein is a set screw N' against the end of which the arm J abuts when it is swung to close the valves. By adjusting this set screw the movement
 50 of the arm J, and consequently the vertical movement of the valves in closing can be stopped at the predetermined point.
 I will now describe the operation of the device, it being understood that the valve F
 60 is what is ordinarily termed the throttle
 65

valve, that is it is the valve which governs the passage of the mixed air and oil or gasoline vapor, or what is ordinarily termed the explosive mixture to the cylinder, while the valve G' is the air admission valve, that is it controls the amount of air which is allowed to mix with the vapor to form the explosive mixture. The entire valve operating mechanism is, first adjusted vertically by screwing the nut J⁴, thus lifting both the arm J and the arm K and consequently the plate J' and this raises both the valves F and the valve G'. This initial adjustment of these valves is such as to give the minimum space between the valve G' and its seat b², when the engine is to run slowly, and this same adjustment leaves the valve F the proper distance above its seat to allow the minimum amount of the explosive mixture to pass to the cylinder. When the valves are in the position shown in Fig. 2 for instance, there is between the valves F and G' such a space as will, when the piston of the engine cylinder is moved to draw in the explosive mixture, give such a vacuum as will draw the proper amount of combustible fluid out of the chamber B' through the passages C into this space between the valves, which I will term the mixing chamber. Here it is mixed with the air which has passed the valve G' and the mixture moved past the valve F and up into the cylinder of the engine. The valves are set initially as shown in Fig. 2, for the engine at low speed. Now to adjust the device for the engine at high speed, the operator swings the arm J horizontally until the pins e, g are opposite the point where the arm K is pivoted to the plate J'. This movement because of the diagonal or wedge shape arrangement of the grooves in the plate J', has thrown the valve G down to its maximum position and the valve F up to its maximum position. The stem K' is then adjusted vertically by means of the nut K², thus moving the arm K vertically and tilting the plate J' until the groove j' assumes more of a horizontal position, and the groove j assumes more of a vertical position, or vice versa as the necessities of the case may require, to the end that the proper vacuum may be attained in the space between the valves F and G' to give a proper mixture for the engine at high speed. The valves have thus been adjusted so that a proper mixture is obtained for the engine both at low speed and at high speed, with the result that when the arm thereafter is swung horizontally by the operator the proper vertical movement is simultaneously given to both the valves F and G' to insure a proper mixture into the engine no matter at what speed it is run.
 It will thus be seen that I have provided a carburetor which will accomplish all the objects set forth in the opening of

this specification, and one which is comparatively simple in construction, easy of adjustment and efficient in operation.

I would have it understood that while I have herein described my invention as applied to a carbureter for use in controlling the admission of an explosive fluid to an explosive engine, yet the invention is in reality of much broader scope. The device can be equally well applied as a regulator 10 for gas engines, as a regulator for gas burners, as a reduction valve, and in fact as a controlling device for any structure where an admixture of air and a combustible fluid is desired. And I would have it understood 15 that while I have illustrated the device in connection with a carbureter for an oil or gasoline explosive engine, yet I do not wish to limit myself to this use, but desire 20 to be understood as contemplating its use in any construction where a mixture of combustible fluid and air is desired.

What I claim is:

1. In a device of the character described, 25 the combination with a source of supply of combustible fluid, of a chamber into which said fluid is admitted, a valve forming one wall of said chamber and controlling the admission of air thereto, a valve forming 30 another wall of the chamber and controlling the exit of fluids therefrom, a sleeve-like stem for one of said valves, a stem for the other valve extending through the first mentioned stem, cam devices for engaging 35 said stems, and means for operating said cam devices.

2. In a device of the character described, 40 the combination with a source of supply of combustible fluid, of a casing having a chamber into which said fluid is admitted, said casing having also oppositely inclined walls 45 extending laterally from the top and bottom of said chamber, a pair of valves located in said casing and forming the top and bottom of said chamber, and means for moving said valves toward and from each other.

3. In a device of the character described, 50 to wit: a casing forming a carbureting chamber; one or more ducts or passages leading thereto from the source of supply of the combustible fluid, a valve for controlling the exit of the mixture from said 55 chamber, a valve controlling the admission of air to said chamber, independent longitudinally movable stems connected respectively to said valves, and cam devices connected with said stems for moving them 60 positively in both the opening and closing directions.

4. In a device of the character described, 65 the combination of the following elements, to wit: a casing forming a carbureting chamber, one or more ducts or passages

leading thereto from the source of supply of the combustible fluid, a valve for controlling the exit of the mixture from said chamber, a valve controlling the admission of air to said chamber, independent 70 longitudinally movable stems connected respectively to said valves, and two wedge shaped devices for moving said stems positively in both the opening and closing directions.

5. In a device of the character described, 75 the combination of the following elements, to wit: a casing forming a carbureting chamber, said casing being channeled so as to connect the source of supply of the combustible fluid to said mixing chamber at a plurality of points, a valve for controlling the exit of the mixture from said chamber, a valve for controlling the admission of air to said chamber, longitudinally movable 80 stems connected respectively to said valves, a plate having two surfaces inclined with respect to each other, one for each of said stems, and a device on each of the stems for engaging said surfaces whereby a movement of the plate operates to move the 85 stems.

6. In a device of the character described, 90 the combination of the following elements, to wit: a casing constituting a carbureting chamber, an air inlet valve for said chamber, a throttle valve controlling the exit of mixture from the chamber, each of said valves provided with stems, a plate having two 95 surfaces inclined with respect to each other, one for engaging each of the stems, and means for tilting said plate to vary the angle of inclination of each said surfaces, means on the stems for engaging the respective surfaces on the plate, and means for moving 100 said plate bodily to operate the valves, whereby when the plate has been tilted to adjust the movement of the valves with respect to each other, the movement of the plate will operate the valves simultaneously. 105

7. In a device of the character described, 110 the combination of the following elements, to wit: the air inlet valve, the throttle valve controlling the exit of the mixture, each of said valves provided with stems, each stem 115 provided with a projection, a curved plate having two inclined surfaces, one for each of said projections, an arm engaged in said plate and adapted to swing the plate longitudinally, and another arm carried by the 120 first named arm pivoted to the plate and adapted to tilt said plate transversely.

8. In a device of the character described, 125 the combination of the following elements, to wit: the air inlet valve, the throttle valve controlling the exit of the mixture, each of said valves provided with stems, each stem 130 provided with a projection, a curved plate having two inclined surfaces, one for each of said projections, an arm engaged in said

plate and adapted to swing the plate longitudinally, another arm carried by the first named arm pivoted to the plate and adapted to tilt said plate transversely, and an adjustable stop for limiting the movement of the first named arm.

9. In a device of the character described, the combination of the following elements, to wit: a hollow casing having an inwardly projecting valve seat, a valve movable from and toward said seat, another projection below the first constituting a second valve seat, and a valve movable to and from said seat, the stem of the first named valve located within the stem of the second named valve, the second named valve seat having one or more passages leading from the source of supply of the combustible fluid, the faces of said valve seats and the valves constituting a mixing or vacuum chamber, a curved plate having two diagonal or wedge shaped surfaces, each of said surfaces engaging one of the said valve stems, means for moving the plate to vary the angle of inclination of said surfaces, and means for moving the plate to operate said stems, and thereby operate the valves.
10. In a device of the character described, the combination of the following elements, to wit: a hollow casing having an inwardly projecting valve seat, a valve movable from and toward said seat, another projection below the first, constituting a second valve seat, a valve movable to and from said seat, each of said valves provided with a vertical

movable stem, the second named valve seat having openings at a plurality of points connected with the source of supply of the combustible fluid, the faces of said valve seats and the valves constituting a mixing chamber, a curved plate having two diagonal or wedge shaped grooves, each of said grooves engaging one of said valve stems by means of the projections, a horizontal swinging arm pivoted to said plate and adapted to move it in a horizontal direction and another arm carried by the first named arm, pivoted to said plate and adapted to tilt the plate to vary the angle of inclination of the grooves.

11. In a device of the character described, the combination with a source of supply of a combustible fluid, a casing having interior oppositely inclined walls, said casing also having an opening connecting the source of fluid supply to the interior of the casing between the adjacent ends of said walls, a pair of valves arranged within said casing on opposite sides of said opening and having their edges extending into proximity to said walls, and means for shifting said valves so as to vary the spaces between the edges thereof and the adjacent walls.

In testimony whereof, I sign this specification in the presence of two witnesses.

LEVI S. GARDNER.
